UNITED STATES PATENT OFFICE.

SAMUEL F. ARBUCKLE, OF INDIANAPOLIS, INDIANA.

SELF-LUBRICATING PISTON.

14,707.

Specification of Reissued Letters Patent. Reissued Aug. 19, 1919.

Original No. 1,294,023, dated February 11, 1919, Serial No. 313,208, filed February 26, 1918. Application for reissue filed March 24, 1919. Serial No. 284,838.

To all whom it may concern:

Be it known that I, SAMUEL F. ARBUCKLE, a citizen of the United States, and a resident of Indianapolis, county of Marion, and 5 State of Indiana, have invented a certain new and useful Self-Lubricating Piston; and I do hereby declare that the following is a full, clear, and exact description thereof, reference being had to the accompanying 10 drawings, in which like numerals refer to like parts.

The object of this invention is the automatic lubrication of the packing of the piston in a cylinder, adapted particularly for 15 utilizing or pumping air or gas so that the device will never leak and have at all times its maximum power and efficiency.

To the foregoing end, one feature of the 20 invention consists in combining with a leather or other packing for a piston, of a lubricating chamber in the piston for containing oil or other liquid lubricating material in contact with the packing so that it will be conveyed by capillary attraction to 25 the surfaces of the packing which engages the cylinder, and thus maintain an air or gas tight joint, and also keep the metal or other packing in good condition so as to contribute to its long life. This lubricating 30 chamber may be made by merely utilizing a hollow piston, as herein shown. There may also be an oil cup secured to the piston rod and communicating with said oil chamber in the piston by means of a conduit piston rod.

35 Another feature of the invention consists in combining with the piston, a disk of leather or other packing material, the annular edge portion of which is bent over and around the piston for furnishing the surface 40 face to engage the cylinder and by making said surface relatively wide so as to obtain a wide bearing surface and thereby avoid the evil effects of wearing action resulting from jarring or vibration of the device 45 while in operation.

The full nature of the invention will be understood from the accompanying drawings and the following description and claims.

50 In the drawings, Figure 1 is a central longitudinal section of a cylinder and piston including my invention.

Fig. 2 is a central longitudinal section of a modified form.

Fig. 3 is a similar section of still another 55 modified form.

There is shown herein a cylinder 10 provided with means 11 at one end for connecting an air or gas conduit. The other end of the cylinder is open and internally 60 threaded to receive a cap 12. A piston rod 13 operates through this cap. The cap has an air vent 14 in it.

The inner portion of the piston rod is reduced to leave a shoulder 15. On the reduced portion a cup-shaped piston 16 is placed, being of somewhat smaller diameter than the cylinder. Over the open end of this cup-shaped piston member a leather washer or disk packing 17 fits, its diameter 70 being great enough for its peripheral portion to be bent back over and around the periphery of the piston and fit tightly between the piston and cylinder. A metal washer 18 is then placed on the piston rod 75 against the packing 17 and it is tightened down by a nut 19. This washer should be of about the same diameter as the piston so as to clamp and hold securely the packing between the piston and the washer. 80

It is seen that this construction leaves a chamber 20 so that the piston is a hollow piston and has in it a chamber for holding oil or lubricating material in a relatively large quantity and in direct contact with 85 the body of the packing. The oil will, of course, by capillary attraction, permeate all parts of the packing and keep it moist and in good condition.

This construction enables such a piston 90 to be used a very long time without any attention to its lubrication. Ordinarily the lubrication is placed in the piston while it is assembled and then left there unless all used, but if desired, a further supply of lubricating material may be furnished by means of an oil cup 21 secured on the piston rod and provided with a conduit 22 leading from the oil cup longitudinally of the piston rod and opening into the chamber 20 in the piston. 100 With this arrangement it becomes unnecessary to disassemble the device in order to charge the piston with oil as it may be supplied at intervals through the oil cup 21 and conduit 22.

In the modified form shown in Fig. 2, the packing is shown turned over the washer instead of the hollow piston. This is where 105

the piston pushes instead of pulls. The principle, so far as lubrication is concerned, however, is the same.

The modified form shown in Fig. 3 reverses the construction shown in Fig. 1 in order to enable the device to be worked in the same situation as in Fig. 2. In other words, in Fig. 3 the hollow piston 16 is on the inner end of the piston rod and the washer is next to the shoulder 15 in said rod. The packing is clamped between them in exactly the same fashion as in Fig. 1, but reversed.

It is seen from the foregoing that such a cylinder and piston may be made air or gas tight and may be lubricated automatically by filling the chamber in the piston with lubricating material in immediate contact with the body of the packing.

20 The invention claimed is:

1. A piston having a closed chamber therein for holding liquid lubricating material, and cylinder packing projecting from said chamber and adapted to transmit lubricating material by capillary attraction to the outside portion of the packing.

2. A piston having a piston rod, an imperforate cup shaped member on said rod with one side open, and a disk shaped packing member on said rod closing the opening in said piston member to form a closed chamber for holding liquid lubricating material and projecting beyond said chamber so that the lubricating material will reach the outside portion of the packing by capillary attraction.

3. A piston rod, an imperforate cup shaped piston member on said rod with one side open, a disk-shaped packing member on said rod and closing the opening in said piston member and forming a chamber for holding liquid lubricating material and extending outward beyond said chamber so as to transmit said material to the periphery thereof by capillary attraction, and a washer on the piston rod of substantially the same diameter as said chamber and on the side of the packing opposite said chamber.

4. A piston rod one end thereof being reduced in diameter to form a shoulder, a cup-shaped piston member on said reduced end with one side open the opposite side engaging said shoulder, a disk-shaped packing member on said rod and closing the opening

in said piston member, and a washer on the 55 piston rod of substantially the same diameter as the hollow piston member and on the opposite side of the packing for pressing the packing against the peripheral edge of said piston.

5. A piston rod, a cup-shaped piston member on said rod with one side open, a disk-shaped packing member on said rod and closing the opening in said piston member and with its peripheral portion overlapping and surrounding said piston member, and a washer on the piston rod of substantially the same diameter as said hollow piston member for clamping the packing tightly against said piston member.

6. A piston rod, a cup-shaped piston member on said rod with one side open, a disk-shaped packing member on said rod and closing the opening in said piston member and with its peripheral portion overlapping 75 and surrounding said piston member, a washer of substantially the same diameter as the hollow piston member and on the opposite side of the packing, and a nut on the rod for clamping said packing between said 80 washer and the hollow piston member.

7. A cylinder, a piston rod therefor with its inner end reduced and threaded and provided with a shoulder, a piston formed of a hollow member open on one side, a washer 85 of substantially the same diameter as the piston and a packing disk between the hollow member and the washer, all three of said last-mentioned elements being on the reduced portion of the piston rod, and a nut 90 on the inner end of the piston rod for clamping said piston thereon against the shoulder.

8. A cylinder, a piston rod, a hollow piston on said rod having a chamber for lubricating material, and a packing disk closing one side of the hollow member and having its peripheral edge overlapping and surrounding said piston, said piston rod being provided with a longitudinal conduit in it extending outside of the cylinder and communicating with the lubricating chamber and the piston whereby said chamber may be supplied with lubricating material externally of the cylinder.

In witness whereof I have hereunto af- 105 fixed my signature.

SAMUEL F. ARBUCKLE
